BOOK COVER PROTECTOR

Albert T. Walraven, Dallas, Tex.

Application July 15, 1935, Serial No. 31,467

7 Claims. (Cl. 281—34)

This invention relates to new and useful improvements in book cover protectors.

One object of the invention is to provide an improved protector formed of a rectangular sheet of material which may be readily applied to books of various sizes.

An important object of the invention is to provide an improved protector wherein each tab which folds over one corner of the book cover is arranged to be bent upon itself so as to give an increased thickness of material and a stronger reinforcing at the corners.

A further object of the invention is to provide an improved one-piece protector which is so arranged that the various tabs and flaps may be formed by tearing along perforated guide lines which eliminates the necessity of any cutting operation to fit the protector to a book cover.

Another object of the invention is to provide an improved protector which is so constructed that a greater area thereof may be coated with an adhesive, whereby the elements of the protector may be more securely fastened together and said protector more adequately held on a book cover, and also whereby said elements are less likely to become detached in use.

Still another object of the invention is to provide an improved protector which is simple in construction and cheap in manufacture, and which may be readily attached by a school child, the arrangement of the protector being such that there is no danger of its being applied in the wrong way to the cover.

A construction designed to carry out the invention will be hereinafter described, together with other features of the invention.

The invention will be more readily understood from a reading of the following specification and by reference to the accompanying drawings, in which an example of the invention is shown, and wherein:

Figure 1 is a face view of the outer side of a protector sheet constructed in accordance with the invention.

Figure 2 is a partial view of the inner or reverse side of said protector, and showing the back tongue folded inwardly.

Figure 3 is a view, similar to Figure 2 and showing one of the side flaps folded inwardly,

Figure 4 is a view, similar to Figure 3 showing the upper and lower flaps folded inwardly,

Figure 5 is a similar view, showing the corner tabs folded inwardly over the outer face of the corner of the protector,

Figure 6 is a partial view of the outer face of

the protector with the flaps and tabs folded as in Figure 5.

Figure 7 is a view similar to Figure 6 and showing the next step,

Figure 8 is a similar view showing the edge of the corner tabs folded inwardly over the side flap to complete the corner, and

Figure 9 is a view showing the side opposite to that in Figure 8 with the corner complete.

In the drawings, the numeral 10 designates a sheet of heavy paper, or other suitable material from which the protector is made. At the top and bottom of the center of the sheet, a pair of diverging perforated lines 11 are provided. These lines may be of any desired length. Extending from the edge of each side and inwardly toward the center of the sheet, a plurality of parallel perforated lines 12 are similarly provided. The outer face of each entire corner of the sheet is gummed or covered with suitable adhesive 13, as clearly shown in Figure 1 and it is pointed out that the area of the gummed surface is a substantial increase over the usual protector of this type.

In fitting the protector to a book, the latter as indicated by the dotted lines A, is laid on the sheet so that its corners B register with one of the perforated guide lines 12. The sheet is then torn along these perforated lines, as is indicated in Figure 1. The sheet is also torn along the perforated lines 11. It is noted that in applying the protector to the cover of a larger book, the cover of said book may overlap the inner ends of the lines 11 and 12. In such case, the sheet need not be torn the full length of the perforations of each line, but the tear can stop in alignment with the edge of the cover.

The book is removed and the sheet 10 is turned over so that its inner face is uppermost as shown in Figure 2. The diverging tears along the lines 11 at the top and bottom of the sheet form top and bottom tongues 14 which are folded inwardly (Figure 2). The book is then laid on the sheet so that its back rests on the tongues 14' which act to reinforce the back. When the sheet has been torn along the lines 12, elongated end flaps 14 are formed and these flaps are folded inwardly over the book cover boards, as shown in Figure 3. As clearly shown in this figure, tearing along the perforated lines 11 and 12 provide top and bottom flaps 15, as well as rectangular shaped corner tabs 16. It is pointed out that this folding exposes a portion of the gummed surface at the top and bottom of each end flap. After the end flaps 14 have been folded down, the top and bottom

flaps are folded inwardly thereover (Figure 4), being fastened thereto by the exposed gummed surface, the rectangular tabs 16 projecting outwardly, as shown. It is pointed out that when 5 the flaps have been so folded, a portion 13' of the gummed surface 13 is on the outer face of each corner, the remainder being on the inner side of the tabs 16.

The next step is to fold the corner tabs 16 10 inwardly over the outer face of the corner of the sheet, as is clearly shown in Figures 5 and 6. This causes the ungummed, or plain side of the tab to overlie the portion of gummed surface 13' at the corner, whereby the tab may be secured 15 thereto. The gummed portion 13' extends only substantially half the length of the tab (Figure 6) whereby only the half nearer the edge of the book cover is glued to said corner.

The inner or unfastened half of said tab 16 20 is then bent so as to overlie itself, as shown in Figure 7. When so bent, the tab is divided into two triangular shaped reinforcing tabs which may be secured together by the gummed surface which is present on the tab 16. It is 25 noted that when the tab is bent, the gummed surfaces on each of the triangular reinforcing tabs formed thereby, lie contiguous to each other. Thus, it will be seen that the innermost tab 17 is secured to the corner by the gummed 30 surface 13' while the topmost tab 17' is secured to the tab therebeneath.

After the tab 16 has been bent upon itself to form the reinforcing tabs 17, it will be seen that a narrow strip 18 extends from the topmost 35 tab beyond the edge of the sheet. This strip, of course, has its inner surface gummed because it is an extension of the topmost tab 17. The strip at each corner is bent inwardly over the top and bottom flaps 15 and are secured there- 40 to, as is clearly shown in Figures 7 and 8. It will be seen that the protector is securely attached and due to the increased gummed surface is securely fastened thereto.

It is noted that the perforated lines 11 and 45 12 not only serve as guide lines in applying the cover but also eliminate the cutting operation, although in some cases it might be desirable to eliminate perforations and merely provide printed guide lines along which the sheet may be 50 cut to form the tongues, flaps and tabs. By bending the corner tabs upon themselves, it will be seen that a triple thickness of material is provided at each corner. This positively reinforces the corner and assures its lasting the 55 life of the protector. The sheet after being torn or cut along the lines 11 and 12 can be folded only the one way to apply it to a cover, which makes its application exceedingly simple. The protector comprises a single rectangular 60 piece of material with a minimum of guide lines, which reduces the manufacturing cost. The rectangular corner tabs folded to overlie themselves provide an increased reinforcing thickness without additional cost or trouble in applying 65 the protector. It is pointed out that when the perforations are employed, the perforated lines which are not torn are covered due to the particular folding of the end and top and bottom flaps, whereby there is no danger of said perforations being torn accidentally after the protector has been applied. Thus, the additional 70 unused perforations, which make for the ad-

justability of the protector to books of various sizes, do not tend to weaken the strength of said protector.

What I claim and desire to secure by Letters Patent is:

1. A book protector having flaps along its top, bottom and outer edges, tabs at each corner of the protector, said flaps being folded inwardly to enclose the covers of a book, each tab being folded outward over the outer face of the corner 10 and then being folded upon itself to reinforce the corner, after which said tab is folded inwardly over the adjacent flap and secured thereto.

2. A book protector having flaps along its 15 top, bottom and outer edges, tabs at each corner of the protector, said flaps being folded inwardly to enclose the covers of a book, each tab being folded outward over the outer face of the corner and then being folded upon itself to 20 form a projecting strip which is folded inwardly over the adjacent flap and secured thereto.

3. A book protector having flaps along its top, bottom and outer edges, rectangular tabs at each corner of the protector, said flaps being folded 25 inwardly to enclose the covers of a book, each tab being folded outward so as to be contiguous to the outer face of the corner, said tab then being folded upon itself to provide a triple thickness of material at the corners.

4. A book protector having flaps along its top, bottom and outer edges, rectangular tabs at each corner of the protector, said flaps being folded 35 inwardly to enclose the covers of a book, each tab being folded outward so as to be contiguous to the outer face of the corner, said tab then being folded upon itself to provide a triple thickness of material at the corners, said folding of the tab providing a narrow strip which is folded inwardly and secured to the ad- 40 jacent flap.

5. A book protector having flaps along its top, bottom and outer edges, rectangular tabs at each corner of the protector, said flaps being folded 45 inwardly to enclose the covers of a book, each tab being folded outward so as to be contiguous to the outer face of the corner and being secured to said face, said tab then being folded upon itself, the folded sections being fastened together whereby a triple thickness of material is 50 provided at the corner.

6. A book protector having flaps along its top, bottom and outer edges, rectangular tabs at each corner of the protector, said flaps being folded 55 inwardly to enclose the covers of a book, each tab being folded outward so as to be contiguous to the outer face of the corner and being secured to said face, said tab then being folded upon itself, the folded sections being fastened together whereby a triple thickness of material is provided at the corner, the folding of said tab providing a narrow strip which is arranged to be folded inwardly and secured to the ad- 60 jacent top or bottom flap.

7. A book protector having flaps along its top, bottom and outer edges, tabs at each corner of the protector, said flaps being folded inwardly to enclose the covers of a book, each tab being folded outward over the outer face of the corner and then being folded upon itself to reinforce 70 the corner.

ALBERT T. WALRAVEN.
